CLAIM

We claim the ornamental design for an absorbent article, as shown and described.

DESCRIPTION

FIG. 1 is a bottom perspective view of an absorbent article showing our new design;

FIG. 2 is a bottom plan view thereof; and,

FIG. 3 is a top plan view thereof.

All sides not shown in the application form no part of the claimed design.

The broken lines shown in FIGS. 1-3 illustrate environment and form no part of the claimed design.

1 Claim, 3 Drawing Sheets

FIG. 1

FIG. 2

FIG. 3
